HAND-BAG CONSTRUCTION

John Ferrara, Brooklyn, N. Y.

Application May 21, 1935, Serial No. 22,509

9 Claims. (Cl. 150—29)

This invention relates to hand-bags.

It is the general object of this invention to devise a hand-bag construction which shall be neat and trim in formation and appearance and at the same time shall be secure and solid in construction; in which the bag material shall be well secured all along its edge so that it will not pucker and be deformed and in which at the same time a minimum of final-assembly 5 fastenings are required.

Further objects of the invention are to achieve the above with the greatest ease of assembly and in particular to do so without crimping metal over the leather or other bag material in assembly, since such operations require special machinery and skilled labor and result in considerable spoilage of expensive leather or other material.

Further objects will become apparent during 20 the course of the following description.

In the drawing,

Fig. 1 is a perspective view of a hand-bag made in accordance with my invention;

Fig. 2 is a horizontal section on the line 2—2 25 in Fig. 1, but with some of the parts spread apart;

Fig. 3 is a vertical section on the line 3—3 of Fig. 1;

Fig. 4 is a sectional view of a modification;

Fig. 5 is a partial elevation of the modification 30 shown in Fig. 4;

Fig. 6 is a sectional view of another modification; and

Fig. 7 is a partial elevation of the modification 35 shown in Fig. 6.

The hand-bag of my invention as illustrated in Figs. 1-3 comprises a frame consisting of two members 10 and 20 pivoted together as at 30. A clip 31 is provided to lock the frame members 40 together.

The frame members have horizontal top flanges 11 and 21 and vertical flanges 12 and 22 running the length of the bag, and end flanges 13 and 23.

The frame members have internally threaded lugs 14 and 24 secured to the outer walls of the vertical flanges 12 and 22, pointing outwardly and preferably ending short of the outer edges of the top flanges.

Vertically rigid spacer blocks or bars 15 and 50 25 of wood or the like fit within the L's formed by the flanges, and are approximately flush with the outer edges of the top flanges. These blocks have holes 16 and 26 therethrough corresponding 55 to the lugs 14 and 24,

To the inner faces of blocks 15 and 25 I attach, preferably by gluing, a lining whose halves are designated as 32 and 42.

The tops of the blocks 15 and 25 are preferably grooved as indicated at 18 and 28, these 5 grooves preferably sloping in slightly from near the outer edges and sloping in steeply from near the inner edges.

The ends of the blocks are grooved the same way, as indicated at 19 and 29.

To the outer faces of the blocks 15 and 25 I attach, preferably by gluing, the bag proper, of leather, fabric, or other material, its two halves being indicated as 33 and 43.

The top edges of the bag member are folded 15 over the tops of the blocks and glued thereto, preferably lying flat against the wider sides of the grooves.

At the ends also a margin of the bag material is preferably folded over and glued in the groove 20 in the same way. The lining also is preferably folded over the edge and down into the groove. The lining and outer bag material are provided with holes corresponding to the holes 16 and 26, the holes being preferably formed all the 25 way through after the lining and outer bag material have been glued to the blocks.

It will be seen that the assembly of my handbag is very simple. The lining and outer bag material are glued to the blocks. The block assemblies are then placed inside the flanged frame members in which they just fit nicely. The grooves in the tops and ends of the blocks facilitate assembly, for they prevent the edges of the leather or other material from catching against 35 the edges of the frame members upon insertion of the block assemblies. Also the grooves provide room at the ends of the blocks for the extra thickness of leather or other material where it is folded at the corners, thus avoiding having 40 either bumps or loose edges.

After the block assemblies have been inserted, headed bolts 34 and 44 are screwed into the internally threaded lugs 14 and 24. These simple 45 operations, which can be performed by practically anyone, complete the assembly of the handbag, giving a neat, simple article, in which the only holding means which show are the heads of the bolts, which can be formed as stars, or as buttons of contrasting color, or in many other 50 ways, to actually enhance the appearance of the hand-bag.

Variations of this construction, generally similar thereto, may be employed. For example, the threaded lugs, holes, and headed bolts may be 55

dispensed with and instead flat-head screws may be screwed into the ends of the blocks through countersunk holes in the end flanges. As another alternative, nuts could be set into the blocks, not visible from the outside, and bolts screwed into them through countersunk holes in the vertical longitudinal flanges.

In Figs. 4 and 5 I have illustrated a modification of my invention in which the general assembly with pivoted double frame is the same as that of Figs. 1-3 but the flanged frame member 50, having horizontal flange 51 and vertical flange 52 and provided with threaded lugs 53, has fitted therein a unitary assembly consisting of a vertically rigid block 54 to which are attached cover member 55 and liner member 56, secured thereto by gluing, by tacks 57 as shown, or otherwise—provided only that the securing points must not be so widely spaced as to allow pulling and puckering of the bag. The block assembly is then fastened on by headed bolts 58.

With this construction it is to be noted that the block, cover, and lining are all assembled to the frame structure at one operation, with a minimum of fastening to be done at this relatively awkward stage, the cover and liner having been fastened to the block beforehand. Also that the block is visible across the top outside the cover member, which makes possible a unique and attractive appearance when the bar is formed of molded plastic, plated metal, or other good-looking material, which preferably is of a color contrasting with the cover material. Also that a minimum of attaching mechanism is visible on the outside, while adequate continuous or closely spaced fastening is provided for the flexible cover material itself.

In Figs. 6 and 7 is shown another modification in which the general assembly with pivoted double frame is the same but in which frame member 60 has horizontal flange 61, vertical flange 62, and studs 63, which need not be threaded. The liner 64 and cover 65 are secured, by gluing, sewing, as illustrated, or otherwise—provided only that the securing points must not be so widely spaced as to allow pulling and puckering of the bag—to a reinforcing bar or block 66. This reinforcing strip need not be thick, but need only serve as a bridge so that if the strip itself is supported at a few points, for example, two, it will be vertically rigid enough to keep the entire top edge of the cover member supported substantially in line, whereby pulling and puckering is avoided. The reinforcing strip 66, cover member 65, and liner 64 have holes corresponding to the studs 63, whereby they fit over the studs and against flange 62. A block or bar 67 has holes 68 bored part way into the inner face thereof into which the studs 63 seat when the block 67 is placed within the angle of the frame member. In this modification end wings 69 are provided on the frame member, and these are bent over the block after insertion thereof. Thus the wings together with flange 62 hold the block into a determined plane, and the studs 63 hold it within that plane. At the same time a minimum of attaching means is visible on the outside and the cover and liner are securely held all the way along by their substantially continuous fastening to the reinforcing strip 66, preferably augmented by a tight frictional fit produced in bending over the wings 69.

It will be understood that many variations from the above embodiments may be made without departing from the spirit of my invention, and

also that the "hand-bag" need not be of the size and shape indicated in the drawing but may be an over-night bag or any kind of purse, bag, or piece of luggage, just so long as it embodies the construction of my invention. Hence I wish to be limited not to the specific forms disclosed herein, but only to the scope of the appended claims, in which the term "hand-bag" is not to be understood as limited to any one type of portable container but rather as applying broadly to any type of "hand-bag" coming within the spirit of this invention.

I claim:

1. A hand-bag comprising a pair of pivoted L-section frame members backed up together and open at their bottom and outer sides, threaded lugs on the non-adjacent faces of the side flanges thereof, a block assembly for each of the frame members, a bag cover member secured to both blocks, holes through the blocks registering with the threaded lugs, and cooperating threaded and headed members extending into the holes in the blocks and securing the blocks to the frame members.

2. A hand-bag comprising a pair of pivoted L-section frame members having their open faces at the bottom and outer sides, blocks to fit within said frame members, a bag cover member extending over the outer faces of the blocks, means to secure said bag cover member to said blocks, a liner extending over the inner faces of the blocks between said inner faces and the frame members, and means independent of said first-mentioned securing means to secure said blocks to said frame members.

3. In a hand-bag a frame member having a longitudinal vertical flange and a longitudinal horizontal flange, a block member fitting within the angle formed by said flanges, a liner between the inner face of the block and the vertical flange and secured to the block, and a cover over the outer face of the block and secured to the block.

4. In a hand-bag a frame member having a longitudinal vertical flange and a longitudinal horizontal flange, a block member fitting within the angle formed by said flanges, means to secure said block member to said frame member, and a bag cover member extending over the outer face of said block and over between the top of said block and the horizontal flange of the frame member, said bag cover member being secured to said block.

5. In a hand-bag a frame member having a longitudinal vertical flange and a longitudinal horizontal flange, a block member fitting within the angle formed by said flanges, means to secure said block member to said frame member, a bag cover member extending over the outer face of said block and over between the top of said block and the horizontal flange of the frame member, and a liner member extending up between the inner face of said block member and the vertical flange of the frame member, said cover member and said liner member being secured to said block member by means independent of the means for flange of the frame member, said cover member

6. In a hand-bag an L-section frame member, an assembly to fit in said frame member comprising a block member having a groove in the top thereof and a bag cover member extending over the outer face of the block member and over the top thereof into said groove, means to secure the bag cover member to the block member, and

- independent means to secure the block assembly within the frame member.
7. In a hand-bag an L-section frame member, an assembly to fit in said frame member comprising a block member having a groove in the top thereof and a bag cover member extending over the outer face of the block member and over the top thereof into said groove, means to secure the bag cover member to the block member, a liner member extending over the inner face of the block member and over the top thereof into said groove, means to secure the liner member to the block member, and independent means to secure the block assembly within the frame member.
8. In a hand-bag having a pair of outwardly and downwardly angled frame members, a cover, a liner, a pair of first blocks fitting within the angles of said frame members and having the top side edges of the cover and liner secured thereto all along their lengths without any large enough spaces between points of attachment to permit pulling and puckering, a pair of second blocks fitting outside said first blocks within the angles of the frame members, means common to blocks of both pairs to prevent endwise and vertical movement thereof, and means acting on the blocks of the second pair to hold both against movement away from the vertical flanges of the frame members.
9. A hand-bag comprising a pair of pivoted L-section frame members, each of said frame members having a vertical inner flange and a horizontal outwardly extending top flange, the bottom and outer side of each of said frame members being completely open and free from additional flanges over such sides, a block fitting within the space defined by the angle of each frame member, said block being of substantial thickness, its outer face being substantially flush with the outer edge of the horizontal flange of the frame member and said block extending a material distance in under said flange, a bag cover member extending up along a side face of each of said blocks, and means for securing said bag cover member in place in relation to said frame members, and means for securing said blocks within the angles of said frame members, said last-named means being so arranged as to be effective in securing said bag cover member in place.

JOHN FERRARA.

CERTIFICATE OF CORRECTION.

Patent No. 2,015,888.

October 1, 1935.

JOHN FERRARA.

It is hereby certified that error appears in the printed specification of the above numbered patent requiring correction as follows: Page 2, second column, line 68, claim 5, strike out the words "flange of the frame member, said cover member" and insert instead securing the block member to the frame member.; and that the said Letters Patent should be read with this correction therein that the same may conform to the record of the case in the Patent Office.

Signed and sealed this 5th day of November, A. D. 1935.

Leslie Frazer
